(57) **CLAIM**

We claim the ornamental design for a band for a wearable device, as shown and described.

DESCRIPTION

FIG. 1 is an isometric view of an embodiment of our design for a band for a wearable device;

FIG. 2 is a top view of the design for a band for a wearable device shown in FIG. 1;

FIG. 3 is a bottom view of the design for a band for a wearable device shown in FIG. 1;

FIG. 4 is a left side view of the design for a band for a wearable device shown in FIG. 1;

FIG. 5 is a right side view of the design for a band for a wearable device shown in FIG. 1;

FIG. 6 is an end view of the design for a band for a wearable device shown in FIG. 1; and,

FIG. 7 is a second end view of the design for a band for a wearable device shown in FIG. 1.

The broken lines in the Figures are for illustrative purposes only and form no part of the claimed design.
